(57) **CLAIM**

We claim the ornamental design for the set of vehicle components, as shown and described.

DESCRIPTION

FIG. 1 is a left front perspective view of a vehicle including a first embodiment of a front light, and showing our new design of the first embodiment of the front light, with the opposing right front perspective view as identical;

FIG. 2 is a front view thereof and noting that the first embodiment of the front light is not visible on the vehicle of FIG. 1 from a rear view of the vehicle;

FIG. 3 is a top view thereof and noting that the first embodiment of the front light is not visible on the vehicle of FIG. 1 from a bottom view of the vehicle; and,

FIG. 4 is a left side view thereof, with the opposing right side view as identical.

The portions of the vehicle and the set of vehicle components shown in broken lines form no part of the claimed design.
